(57) **CLAIM**

I claim the ornamental design for the hinge pin removal tool, as shown and described.

DESCRIPTION

FIG. 1 is a first perspective view of the hinge pin removal tool;

FIG. 2 is a second perspective view thereof;

FIG. 3 is a front view thereof;

FIG. 4 is a back view thereof;

FIG. 5 is a side view thereof;

FIG. 6 is a side view thereof showing the side opposite that shown in FIG. 5;

FIG. 7 is a top view thereof; and,

FIG. 8 is a bottom view thereof.

The broken lines depict portions of the hinge pin removal tool in which the design is embodied that form no part of the claimed design.
